MACHINE FOR INSERTING FASTENINGS

Robert H. Lawson, Beverly, Mass., assignor to
United Shoe Machinery Corporation, Flemington, N. J., a corporation of New Jersey

Application March 14, 1945, Serial No. 582,647

13 Claims. (Cl. 1—29)

1

This invention relates to an improved method of and a machine for inserting fastenings into work pieces, such as shoe parts, and is herein illustrated as applied to the attachment of shoe uppers to ribbed sole members after portions of the upper of each shoe have been worked into lasted relation to the sole member. Ribbed sole members are, for example, used in the form of lipped insoles in the manufacture of welt shoes.

In the manufacture of welt shoes, particularly of the Goodyear type in which the margin of the upper is secured in lasted position to the insole lip, it is common practice to employ fastenings, such as two-legged staples, to secure the upper to the insole lip, each staple being inserted straight through the upstanding margin of the upper and the insole lip and the end portions of the staple legs emerging from the rear side of the insole lip being flared apart and clinched against the rear side of the insole lip by an anvil or the like.

It is an object of the present invention to improve upon fastening inserting methods and machines of the type referred to, and particularly to insure that the inserted fastenings have considerable holding power albeit they preferably are, in a sense, single-legged fastenings, and that the accuracy of their formation is consistent and thus their insertion uniform.

It is another object of the invention to provide an improved fastening inserting method and machine whereby a fastening which preferably and as illustrated comprises a straight piece of fastening material, such as wire, is inserted endwise and caused to pierce the entire thickness of the work, the insertion being so controlled that the driven fastening resembles a staple the opposite ends of which are anchored within the work so as not to interfere with succeeding operations, such as the inseam sewing operation in the illustrated example of a Goodyear welt shoe.

In one important aspect the invention accordingly provides a novel and improved method of inserting through-and-through fastenings (i. e. fastenings which pierce the entire thickness of the work) according to which each fastening is driven straight through the work from one side thereof until the trailing end of the fastening is embedded in the work below the work surface at that side. The leading end portion of the fastening is caused to emerge from the opposite side of the work during the driving of the fastening, the leading end portion, however, being turned back into the work and caused to reemerge from the side of entry thereof, where it is deflected a

2

second time and reinserted in the work at the side of entry so as to anchor that end portion in the work and embed the extremity thereof beneath the work surface.

5 In another important aspect the invention provides a novel and improved fastening inserting machine adapted for use in the practice of the above-mentioned method and provided with a throat member adapted to engage one 10 side of the work and a fastening deflecting member or anvil adapted to engage the opposite side of the work. A driver movable in the throat member serves to insert each fastening endwise through the throat member into and through 15 the work until the trailing end of the fastening is embedded or countersunk beneath the surface of the work engaged by the throat member. The anvil serves to engage the leading end portion 20 of the fastening when emerging from the side of the work engaged by the anvil and to turn it back into the work causing it to reemerge from the side of entry of the work. Moreover, the throat member is provided with a clinching cavity 25 which receives the reemerging leading end portion of the fastening and turns it back into the surface of the work engaged by the throat member. Thus the fastening inserted into the work has 30 the form of a staple the opposite ends of which are securely anchored inside of the work where they can not form dangerous or annoying obstructions, and only portions of the thin smooth shank of the driven fastening are visible on opposite sides of the work.

35 While the invention is thus disclosed herein in its application to the attachment of shoe uppers to lipped sole members, it will be recognized that in a more general aspect the invention provides a novel method of and a machine for inserting fastenings not limited in utility to the 40 fastening of uppers nor to shoe manufacture. In fact, the illustrated machine may be used to good advantage for the insertion into work pieces of straight fastenings, not bent or clinched in any way, such as for the attachment of toplifts to 45 heels by wire slugs, it being necessary in such a case merely to remove the anvil.

These and other features of the invention will 50 now be described in detail with reference to the accompanying drawings and will be pointed out in the appended claims.

In the drawings,

Fig. 1 is a view in right hand side elevation 55 of the principal parts of a machine embodying

the present invention, with certain parts of the machine broken away;

Fig. 2 is a view in right hand side elevation of mechanism for operating the throat member or wiper and the driver and of wire feeding mechanism with which the machine illustrated in Fig. 1 is provided;

Fig. 3 is a view in left hand side elevation of the present machine, illustrating particularly mechanism for operating wire severing and fastening transferring means;

Fig. 4 is a plan view of the machine illustrated in Fig. 1, with certain parts broken away;

Fig. 5 is a detail view of the wiper head and associated mechanism;

Fig. 6 is a sectional view, taken along the line VI—VI of Fig. 5;

Fig. 7 is a sectional view taken along the line VII—VII of Fig. 5;

Fig. 8 is a plan view of the wire feeding mechanism;

Fig. 9 is a detail view, in plan, of gripper controlling mechanism;

Figs. 10 to 12 illustrate different steps in lasting and overwiping an upper and securing it in lasted position; and

Fig. 13 is a plan view of a section through the throat member with a work piece presented thereto, illustrating the driving of the fastenings.

It has been stated that the present invention involves, inter alia, a novel and improved method of inserting fastenings into a work piece. In the illustrated example the work piece is a shoe comprising an upper U (Figs. 1, 10-13) on a last L, the last carrying on its bottom a ribbed or lipped insole I into lasted relation with which the upper is worked and then secured in this relation by fastenings inserted through the margin of the upper and the lip of the insole. The fastening used in the practice of the present invention is a single-legged fastening in the sense that it comprises a single straight piece of wire or similar fastening material. After the upper U has been tensioned on the last L and its margin worked into lasted relation to the feather portion and lip of the insole I, the fastening is inserted endwise straight through the margin of the upper and the lip, the trailing end of the fastening finally becoming embedded or countersunk in the surface or side of the work whence it was driven (hereinafter referred to as the side of entry) and the leading end portion of the fastening emerging from the opposite surface or side of the work which, in the present case, is the rear side or inner side of the insole lip. A deflecting member or anvil is held in engagement with the rear side of the insole lip in a position to engage the emerging leading end portion of the fastening and to turn it back into the work as the driving of the fastening continues, with the result that the leading end portion of the fastening is caused to penetrate again the entire thickness of the work (lip and margin of shoe upper) in a reverse direction and to re-emerge at the side of entry of the work. The re-emerging leading end portion of the fastening is engaged by another deflecting member or clinching member which causes that portion of the fastening to be turned back into the side of entry at a point between the point of entry and the point of reemergence so as not to interfere with the countersunk trailing end of the fastening and so as to form a staple-like driven fastening which resembles a closed ring with the opposite ends overlapping and anchored well

within the work. Thus the ends can not interfere with or impair succeeding operations in the processing of the shoe, such as the inseam sewing operation.

The illustrated machine is particularly adapted for use in practicing the above-described method but, as previously pointed out, it is by no means limited in its utility to the insertion of fastenings into shoe parts of the aforementioned type or shoe parts in general.

General organization of the machine

The principal operating instrumentalities of the machine and their actuating mechanisms are contained in or secured to a box-like frame 20 (Figs. 1 to 4) which is adapted to rest on a support (not shown). The principal work engaging operating instrumentalities of the illustrated machine are a stationary anvil 22 (Figs. 1, 3, 10 to 13), an upper tensioning gripper 24, and a wiper 26 through which the fastenings are inserted, by mechanism to be described, into the work, the latter being manually presented to the machine in a position in which the anvil 22 engages the rear face or inner side of the lip of the insole I on the bottom of the last L over which the upper U is to be tensioned by the gripper 24. The anvil 22, of course, is caused initially to engage and support that portion of the insole lip where the fastening inserting operation is to begin, the operation being repeated and progressing along the lip first at one side and then at the other side of the insole while the shoe is held in the operator's hands and is successively moved or fed by him with relation to the machine to present different portions of the shoe successively to the operating instrumentalities of the machine.

The actuating mechanisms of the various movable operating instrumentalities of the machine are driven from a single cam shaft 28 (Figs. 1 to 4) extending transversely of the machine and arranged for rotation in suitable bearings provided in the frame 20. The cam shaft 28 is driven by connections (not shown) to a suitable source of power, the connections including an operator controlled clutch (not shown) which, when maintained engaged, will continue to rotate the cam shaft and thus cause the machine to run through an indefinite number of cycles, one cycle corresponding to one complete revolution of the cam shaft.

The gripper mechanism

For tensioning the upper U of a shoe presented to the machine in the position illustrated in Fig. 1, heightwise of the last, the illustrated machine is provided with the previously mentioned gripper 24 comprising two jaws 30 and 32 (Figs. 1, 10, 11, 12) which are rotatable about a common pivot pin 34 and which have upward extensions provided with slots 36, 38 inclined with relation to each other. A transverse pin 40 extends through both slots 36, 38 and is carried at opposite ends by parallel links 42 (Figs. 1, 9) pivotally secured at their upper ends to parallel arms 44 mounted for free rotary movement on a transverse rod or shaft 46 fast at opposite ends in the frame 20. As will be described, the pin 40 is movable heightwise of the machine so as to open and close the gripper jaws. Upward movement of the pin 40 in the slots 36, 38 closes the gripper 24. The heightwise movement of the pin 40 is produced by rocking the parallel arms 44. To this end each arm 44

has an upwardly and rearwardly extending projection 48, the two projections 48 being interconnected by a web 50. Each projection 48 has secured to it a rearwardly extending rod 52 which passes through a boss provided at the upper end of an arm 54, each arm being freely rotatable about the rod 46. A spring 56 is mounted on each rod 52 and is confined between the boss of the arm 54 at one end and nuts 58 on the rod at the other end. As will be noted, operation of both arms 54 in a clockwise direction, as viewed in Fig. 1, will produce a yielding movement in the same direction of the parallel arms 44, with the result that the pin 40 will be elevated to close the gripper. Thus the gripper is closed by a 10 yieldingly operating mechanism. The two arms 54 are interconnected by a web 60 (Fig. 9). The right hand arm 54 (as viewed from the front of the machine) is part of a two-armed lever 62 (Fig. 1) rotatable about the rod 46 and carrying at its lower end a cam roll or cam follower 64 held against the periphery of a cam disk 66 on the shaft 28 by a torsion spring 68 (Figs. 4 and 9) coiled about a spacer 69 between the hub of the lever 62 and the bearing of the rod 46, one end of the spring 68 being in engagement with the lever 62 and the other end with a fixed portion of the frame. Rotation of the cam disk 66 thus causes operation of the transverse pin 49 to open and close the gripper. However, this motion is utilized not only for opening and closing the gripper but for moving the gripper heightwise of the machine either to tension the upper after it has been seized by the gripper or to move the gripper into a position in which it can seize the margin of the upper. As has been pointed out, in the lowermost position of the pin 40 the gripper jaws are open and, assuming that the gripper itself is positioned at the lower end of its heightwise travel, it is to be noted that the movement of the lever 62 by the cam disk 66 in a clockwise direction, as viewed in Fig. 1, will cause an upward movement of the transverse pin 40, with the result that the gripper jaws are closed upon the margin of the upper presented thereto, while the gripper remains in its lowermost position. It is only after the gripper jaws have been firmly closed upon the margin of the upper that the gripper begins its heightwise movement to tension the upper heightwise of the last. To accomplish this the upper extension of the gripper jaw 30 is pivoted by a pin 71 to an arm 70 (Figs. 1 and 9) rotatably mounted on the rod 46. The pin 71 is the main support of the entire gripper 24 which is adapted to move about the pin 71 in a direction transverse to the shoe presented to the machine. The arm 70 is connected by a link 72 (Fig. 1) to a friction device or retarder 74 of a conventional type which functions to prevent an upward movement of the gripper jaws while they are being firmly closed upon the upper. On continued upward movement of the transverse pin 40 after the closing of the gripper the resistance of the friction device 74 is overcome and the gripper is moved heightwise of the machine, moving the arm 70 at the same time in a clockwise direction (Fig. 1) about the rod 46. Reversely, when the gripper is in its elevated position with the jaws closed, downward movement of the transverse pin 40 serves to open the gripper jaws while the gripper is maintained in its uppermost position due to the retarding action of the friction device 74, which action is overcome, only after the gripper jaws have been 70

opened, by the continued downward movement of the transverse pin. As illustrated in Fig. 1 the cam disk 66 is provided near its high portion with a depression or dip 76 which reaches the cam roll 64 after the high portion has passed it and causes in the elevated and upper tensioning position of the gripper a slight opening of the jaws to permit slippage of the margin of the upper when the latter is being worked into lasted relation to the insole.

The wiper head or throat member

To wipe each portion of the upper U over the insole feather and against the upstanding lip of the insole I after that portion of the upper has been tensioned by the gripper and is held under tension, there is provided a wiper head 80 (Figs. 1, 3, 5) which also functions as a throat member or nozzle in that the fastenings are inserted into the work through that member. The wiper head 80 is of a substantially rectangular shape having a tapering front end and being arranged for reciprocating movement substantially in a horizontal path into and out of engagement with the shoe presented to the machine. The wiper head 80 comprises a main portion 82 (Figs. 5, 6) which is provided at its right hand side (as seen from the front of the machine) with a cover plate 84. The wiper head is supported for movement toward and from the work on a front link 86 (Figs. 1 and 2) and a parallel back link 88, the two links having the same effective length. The upper ends of the links are pivotally connected to the wiper head 80. The lower end of the front link 86 is mounted to rotate freely on a rod 90 secured in the machine frame and the lower end of the back link 88 is mounted to rotate freely on a rod 92 secured in the machine frame. Pivotal connection between the upper end of the front link 86 and the wiper head 80 is established in the following manner. Secured to the left hand side of the wiper head 80 is an outwardly and downwardly extending bracket 94 (Figs. 3 and 6) 45 which carries a horizontal pin 96 extending through a slot 98 provided in the upper end of the front link 86. Thus a lost motion is provided between the link 86 and the wiper head for purposes to be described. To actuate the wiper head 50 there is provided a bell crank lever 100 (Fig. 2) which acts yieldingly on the front link 86 to advance the wiper head 80 toward the work. One arm of the bell crank lever 100 carries a roll or cam follower 102 engaging a cam groove provided in one face of a cam disk 104. The just mentioned yielding operation of the link 86 by the bell crank lever 100 is accomplished in the following manner. There is provided in the front link 86 a socket 106 and a similar socket 108 is provided in the upwardly extending arm of the bell crank lever 100. The two sockets are axially aligned and house a spring 110 surrounding a headed bolt 112 extending from the front side of the link 86 through both sockets and through to the rear side of the upwardly extending arm of the bell crank lever 100 where it carries lock nuts bearing against said arm. As will be noted from an inspection of Fig. 2, movement of the bell crank member 100 in a counterclockwise direction will cause a yielding movement of the link 86 in the same direction to advance the wiper head toward the work but movement of the bell crank member 100 in a clockwise direction will produce a positive movement of the link 65 75 86 in the same direction for purposes to be de-

scribed, this being due to the provision of the bolt 112 and the lock nuts carried by it.

It should be noted that since the two links 86, 88 carrying the wiper head 80 have the same effective length, a parallel motion results. The rearward movement of the wiper head 80, which is produced by separate mechanism to be described, is adjustably determined by the following mechanism. The back link 88 is provided with a tail piece 114 which has a socket 116 carrying a screw 120 secured in place by a nut 122, the lower end of the screw on rearward movement of the wiper head 80 being adapted to engage an abutment 118 provided on the lower portion of the machine frame.

The wire feeding mechanism

As previously explained the fastenings to be inserted by the illustrated machine are formed therein from a continuous strand of fastening material, such as wire, which is fed forwardly in the machine step by step and the leading end portion of which is severed to form a single-legged straight fastening. The strand of fastening material is preferably wound up on a reel (not shown) which is conveniently mounted for rotation on the machine frame and from which the wire passes through suitable guides (not shown) into a wire feeding mechanism. The wire feeding mechanism includes an intermittently rotated feed wheel 130 (Fig. 8) with which cooperates a pressure wheel 132, the wire passing between the two wheels. The pressure wheel is rotatably mounted in a supporting lever 134 pivotally secured at 136 to a rearward extension 138 of the main portion 82 of the wiper head. The wheel 132 is urged toward the feed wheel 130 and to this end there is provided a bolt 140 one end of which is in threaded engagement with a tapped hole provided in a shoulder portion of the rearward extension 138. The bolt 140 extends through a hole provided in a tail piece 142 of the supporting lever 134 and carries a spring 144 which is compressed between the head of the bolt and the tail piece, the spring thus tending to rotate the supporting lever 134 in a counterclockwise direction, as viewed in Fig. 8, so as to urge the wheel 132 into engagement with the wire and to hold the wire against the feed wheel 130.

Mechanism is provided for rendering the wire feeding mechanism inoperative and to this end there is pivotally secured to the rearward extension 138 a hand lever 146. The hub portion of the hand lever is slabbed off at one side to permit the supporting lever 134 to be so rotated that the pressure wheel 132 is moved into operative position in engagement with the wire. Rotation of the hand lever 146 causes the round part of the hub of that lever to engage a right hand extension of the supporting lever 134 and rotate this lever in a clockwise direction, as viewed in Fig. 8, thus moving the pressure wheel 132 away from the feed wheel 130 and interrupting the operation of the wire feeding mechanism.

The feed wheel 130 is loosely rotatable on a vertical stub shaft 148 which is rotatably mounted in bearings provided in the rearward extension 138. The stub shaft 148 is adapted to be rocked and to this end carries a pinion 150 secured to the lower end thereof. Loosely rotatable on the stub shaft 148 and fixedly secured to the feed wheel 130 is a ratchet wheel 152 which is adapted to be engaged by a pawl 154 pivotally carried on an arm 156 clamped to the stub shaft

148. The pawl 154 is biased by a spring 158 to engage a tooth of the ratchet 152 so that upon movement of the arm 156 in a counterclockwise direction, as viewed in Fig. 8, the ratchet 152 and the feed wheel 130 will be rotated. On reverse movement of the arm 156 in clockwise direction, the pawl 154 is caused to ride idly back over the teeth of the ratchet wheel 152 so as to engage, after the conclusion of this idle motion, another tooth of the ratchet wheel, preparatory to imparting another forward rotation to the ratchet wheel 152 and the feed wheel 130.

The amount of rotation imparted to the feed wheel 130 determines the extent of the wire feed and thus the length of the fastening to be formed from the wire. This amount is adjustable and to this end there is provided a pawl-like shield or guard 160 adapted to mask a portion of the ratchet wheel 152. The shield 160 is pivotally secured at 162 to an arm 164 loosely rotatable on the stub shaft 148. The shield 160 is so arranged that it is adapted to mask that portion of the ratchet which the pawl 154 would normally engage at the conclusion of its idle backward motion. A pin 166 carried by the arm 164 has coiled about it a spring 168 one end of which is in engagement with the pivot pin 162 and the other with the shield so as to hold the latter in engagement with the ratchet wheel 152. As will be noted from an inspection of Fig. 8, the pawl 154, when moving backward on its idle stroke, is caused to ride up upon the shield 160, with the result that part of its succeeding forward motion is idle in the sense that it does not produce any motion of the ratchet 152 until the pawl 154 has moved out of engagement with the shield 160 and has dropped into the tooth of the ratchet wheel 152 located at the end of the shield 160. The position of the shield 160 with relation to the ratchet wheel 152 is adjustable by an adjusting movement of the arm 164 about the stub shaft 148. For this purpose the arm 164 is provided at its outer end with a segment 170 having on its top face a series of depressions 172 one of which is engaged by a latch 174 formed on a hand grip 176 pivotally secured at 178 (Fig. 2) to the rearward extension 138 of the wiper head. The lower portion of the hand grip 176 is engaged by a spring pressed plunger 180 which serves to maintain the latch 174 in engagement with one of the depressions 172 so as to hold the arm 164 in its adjusted position. As the feed wheel 130 is rotated the wire gripped thereagainst by the pressure of the wheel 132 is advanced and is fed into a tube 182 (Figs. 5, 8) which is clamped at 184 to the rearward extension 138 of the wiper head. The front end of this tube is inserted into a bore provided in a wire intake 186 (Figs. 5, 7) which fits in a slot in the cover plate 84 to which it is secured. The wire intake 186 has a wire passage 188 through which the wire is passed into a bar-shaped guide member 190 seated flush in a longitudinal slot in the back of the cover plate 84. The guide member has on its exposed face a longitudinally extending groove along which the wire is passed, the open side of the groove being covered by the main portion 82 of the wiper head. Thus the wire is supported all around during the entire course of its travel into the wire severing location.

As described above, the wire feeding mechanism derives its motion from the pinion 150 secured to the stub shaft 148 and this pinion is adapted to be rocked by a rack bar 192 (Fig. 8) which is reciprocated in a slideway 194 provided in the

above-mentioned shouldered portion of the rearward extension 138 of the wiper head. Movement of the rack bar 192 toward the right of Fig. 8 causes rotation of the pinion 150 in a counterclockwise direction, as viewed in Fig. 8, and thus causes a wire feeding motion to be imparted to the feed wheel 130. The movement of the rack bar 192 toward the right of Fig. 8 takes place against the resistance of a spring 196 located in the slideway 194, one end of the spring engaging the end of the rack bar and the other end of the spring being backed by a screw 198 threaded into the open end of the slideway 194. The main purpose of the spring 196 is to return the rack bar 192 and mechanism associated therewith into their initial positions after a wire feeding motion has been imparted to the feed wheel 130. The movement of the rack bar 192 in either direction is limited in that a lateral pin 200 (Fig. 2) secured to the rack bar extends through a slot 202 provided in the outer wall of the slideway 194. The forward end of the rack bar is pivotally connected by a double link 204 to a two-armed lever 206 rotatably secured by a fulcrum stud 208 to the wiper head. The lever 206 carries at its lower end a cam roll or cam follower 210 which is held in engagement with a cam 212 secured to the cam shaft 28.

The wire severing and fastening transferring mechanism

As has been stated, the leading end portion of the wire, each time the wire has been advanced in the machine, is cut off to form a fastening which, then, is inserted endwise into the work. To this end there is mounted in a circular recess 214 (Fig. 6) provided in the front end portion of the wiper head 80 a rotatable wire receiving roll 216 provided on its inner surface with a diagonally extending groove adapted to receive the leading end portion of the wire when the wire is being advanced in the machine. This groove is covered or bridged over by a disk or roll 218 of the same diameter as the roll 216 which it abuts, the disk 218 being located in a circular recess provided in the cover 84. The disk 218 is secured to the roll 216 by screws or the like. The roll 216 and disk 218 are adapted to be rotated between two end positions, namely a wire receiving position, in which the groove in the roll 216 is aligned with the groove of the wire guiding member 190, the lower end of which terminates in close proximity to the periphery of the roll 216, and a fastening driving position or fastening presenting position in which the groove in the roll 216 is aligned with the path of movement of a fastening inserting driver. To rotate the roll 216 it is provided with a laterally extending stem 220 (Figs. 3 and 6) to which is secured an arm 222. The arm extends upwardly in a rearwardly inclined direction and its upper end is pivotally connected by a link 224 to a horizontal rod 226 of substantial length. The rear portion of the rod 226 carries two collars 228 and 230 between which the rod extends through a bushing 232. Springs 234 and 236 are carried on the rod 226 and are located between the bushing 232 and the collars 228 and 230 respectively. The bushing 232 is pivotally secured to the upper end of a lever 238 freely rotatable on the rod 92 and integral with a lever 240 carrying on its extremity a cam roll 242 which is in engagement with a cam groove provided in one side of the cam disk 104. Rotation of the levers 238, 240 by the cam groove in one direction or the other thus causes the wire receiving roll 216 to be rotated between the above-

described two predetermined positions. To limit and adjust the movement of the horizontal rod 226 in either direction so as to determine accurately the two positions of the roll 216, there is secured in a socket 246 (Fig. 4) provided in the rearward extension 138 of the wiper head a pin 248 (Fig. 3) on which is mounted a split sleeve 250 adapted to rotated slightly about the pin 248. The two ends of the split sleeve have oppositely extending internal threads which are engaged by screws 252, 254. The screws are bored centrally to permit the passage therethrough of the rod 226 which also passes through the sleeve 250. The rod has fixed to it collars 256, 258 which, on movement of the rod in one direction or the other, are caused to abut against the heads of the screws 252, 254 to limit movement of the rod 226. The screws are adjustable and they are held in adjusted position by binding screws 260 engaging the split sleeve 250 and binding the screws 252, 254 against the threaded portions of the sleeve which they engage. Continued operation of the levers 238, 240 after one of the collars 256, 258 has engaged one of the screws 252, 254 is made possible owing to the arrangement of the springs 234, 236 which, in this case, will be compressed and thus serve the further purpose of holding the wire receiving roll 216 in either one of its two predetermined positions by spring pressure so that the roll may not be jarred out of alignment with the wire guiding passage or the path of movement of the driver by any vibration of the machine. When the roll 216 is rotated out of its wire receiving position, the length of wire extending therein is severed from the wire strand due to the shearing action between the roll and the wire guiding member 190.

The fastening driving mechanism

For inserting fastenings into the work presented to the machine there is provided a reciprocating driver 262 (Figs. 5 and 6) which, in the illustrated example, is extremely thin and of the same gage as the wire from which the fastenings are formed. The driver is movable in and with relation to the wiper head 80 and, as will be described, it is guided and covered all around and over its entire length during the entire course of its travel. The driver 262 is movable in a bar-shaped guiding member 264 of rectangular cross section which is seated flush in a longitudinal recess provided in the back face or inside face of the cover 84. The guiding member 264 has extending along the exposed face thereof a groove which serves as the driver passage and which is covered or bridged over, as will be presently described. The driver 262 is connected to a driver bar 266 which is reciprocated in a longitudinal recess provided in the main portion 82 of the wiper head. To hold the guiding member 264 in place there is provided a stop pin 268 (Fig. 6) driven into the cover 84 and abutting the rear end of the guiding member 264 the front end of which is positioned in close proximity to the roll 216. The driver 262 is secured to the driver bar 266 as follows. The rear end of the driver has a lateral fin 270 which extends into a slot provided in one end of a pin 272 carried by the driver bar 266. The rear end of the driver 262 is engaged by a hardened pin 274 also carried by the driver bar 266 and positioned in tangential relation to the pin 272. The pin 274 is provided with a ridge which extends into the groove of the guiding member 264 and engages the rear end of the driver. As illustrated in Figs. 2 and 6, there is pivotally con-

nected to the rear end of the driver bar 266 a link 276 which in turn is connected to a driver actuating lever 278 arranged to swing about a fixed rod 280 and adapted to be rotated by a torsion spring 282 coiled about the hub of the lever 278, one end of the spring engaging a pin 284 on the actuating lever 278 and the other end engaging a pin 286 carried by the above-described link 88 supporting the wiper head 80. The actuating lever 278 is adapted to be held in a cocked position, with the torsion spring 282 loaded, by the engagement of a locking pin 288 provided on the lever 278 with a latch 290 pivotally secured to the link 88 and having a depending arm 292 the lower end of which is connected by a link 294 to an arm 296 mounted for free rotation about the rod 280 and provided with an elongated hub 298 to the other end of which is secured a similar arm 302 (Fig. 1) carrying a roll 306 adapted to be engaged by the high portion of a cam 306 on the cam shaft 28. As will be noted, the just described cam operated mechanism is adapted to release the actuating lever 278 to the force of the loaded spring 282 by tripping the latch 290. The fulcrum pin of the latch 290 has coiled about it a torsion spring 304 which tends to hold the latch 290 in its elevated locking position and against the resistance of which the latch is depressed by the above-described cam operated mechanism. The latch 290 has a forwardly extending shelf 308 along which the pin 288 moves after the tripping of the latch on forward and rearward movement of the lever 278.

The driver actuating lever 278 is connected to the above-described bell crank lever 100, which serves to actuate the wiper head, by a link 310 the left hand end of which (Fig. 2) is pivotally secured to the upwardly extending arm of the bell crank lever 100 and the right hand end of which is provided with a slot 312 which is engaged by a pin 313 carried by the driver actuating lever 278. When the wiper head 80 is advanced by the counterclockwise rotation (Fig. 2) of the bell crank lever 100 and the front link 86, the pin 96 carried by the wiper head 80 is located at the rear end of the slot 89 (Fig. 3) provided at the upper end of the link 86 so that the wiper head 80 is pulled forwardly by the link 86, the link 88 swinging freely about its rod 92. In view of the link connection 310 between the bell crank lever 100 and the driver actuating lever 278 and, furthermore, due to the fact that, at that time, the pin 313 is located at the rear end of the slot 312, the driver actuating lever 278 is advanced with the wiper head, with the result that the wiper head 80 and the driver 282 are moved as a unit toward the work. It is to be noted that this advance of the driver and its actuating lever 278 takes place while the actuating lever 278 is held cocked by the latch 290 which, due to the fact that it is carried by the link 88, is advanced concomitantly with the lever 278. After the wiper head 80 has moved into engagement with the work and has wiped the upper into lasted relation to the insole, the high portion of the cam 306 becomes active to trip the latch 290 so as to release the actuating lever 278 to the loaded spring 282 which is of considerable strength. This results in the operation of the driver which is moved forwardly in the guide member 264 and through the wire severing roll 216 while the latter is in its fastening inserting position so as to insert the fastening contained in the roll into the work. This movement of the driver, of course, takes place with relation to the wiper head which is held stationary and in en-

gagement with the work. The relative movement between the driver and the wiper head, after the latter has reached its operative position, is possible due to the provision of the slot 312 in the link 310, enabling the driver actuating lever 278 to be propelled forwardly by the spring 282 while the wiper actuating mechanism to which it is connected remains stationary. Reversely, when the bell crank lever 100 is rotated by its cam 104 in a clockwise direction, as viewed in Fig. 2, the wiper head 80 is not directly affected by this motion of the bell crank lever 100, this being due to the lost motion provided between the front link 86 and the wiper head by the slot 98. However, since the lost motion provided between the bell crank lever 100 and the driver actuating lever 278 by the slot 312 has been taken up as a result of the driver operating forward movement of the lever 278 with relation to the link 310 causing the pin 313 to move to the forward end of the slot 312, the driver actuating lever 278 is immediately moved backward on initiation of the above-mentioned clockwise rotation of the bell crank lever 100. This backward movement of the lever 278 serves the purpose of loading the torsion spring 282 and cocking the lever 278. Since one end of the spring 282 bears against the rear link 88 supporting the wiper head 80 the rear link 88 also is swung rearwardly thereby retracting the wiper head 80. As described, the rearward movement of the link 88 and the wiper head is terminated by the engagement of the screw 120 with the abutment 118 thus enabling the driver actuating lever 278 to move fully into its cocked position, it being understood that the slot 98 is of sufficient length to permit such movement of the lever 278, the bell crank lever 100 and the front link 86.

The operative movement of the driver is limited and the extent of this movement is adjustable by the provision of a rod 314 (Figs. 1 and 2) pivotally secured to the driver actuating lever 278 and extending through an aperture 316 provided in the link 88. The rod 314 carries at its rear end a bumper 318 adjustably secured on the rod. The bumper, on operation of the driver, is adapted to strike against the rear face of the link 88 thus terminating the operative movement of the driver. This has the additional advantage of forcing, due to the impact of the bumper 318 against the link 88, the wiper head 80 into intimate contact with the work while the fastening is inserted.

As already mentioned, the driver on its operative stroke moves through the groove provided in the wire receiving and severing roll 216, the roll, of course, first having been rotated into the fastening inserting position in which its groove is in alignment with the driver passage of the guiding member 264. Between the roll 216 and the outer end of the wiper head 80 is provided a nozzle piece 320 (Fig. 6) having a projection or stem 322 extending into a hole provided in the main portion 82 of the wiper head. The nozzle piece 320 is grooved similar to the wire receiving roll 216 and its groove is in alignment with the driver passage and the groove in the roll 216 when the roll is located in its fastening inserting position. The nozzle piece 320 is engaged by a cover piece 324 which also has a projection or stem 326 engaged in a hole provided in the cover plate 84. Moreover, the visible front end of the cover piece 324 has a clenching cavity 328 which serves to engage the leading end portion of the fastening when it reemerges from the side of entry of the work and to curve that portion to cause it to re-

enter the work, as has been described. The clenching cavity 328 is so shaped that the extremity of the leading end portion of the fastening is caused to reenter the side of entry of the work at a point located between the point of entry and the point of emergence.

It will be noted that as a result of the provision of the longitudinal recess in the main portion 82 of the wiper head 80 to accommodate the driver bar 266, the driver can not be covered by the main portion 82 over the entire extent of its travel in the groove provided in the guide member 264. However, to insure nevertheless that the thin driver is fully supported in any position of its reciprocation, there is provided a movable guard member 330 (Figs. 5, 6 and 12) which has somewhat the shape of a long hatchet and is located in a recess provided in the main portion 82 of the wiper head. The guard member 330 has a curved face 331 located in close proximity to the complementary curved front face 333 of the driver bar 266 and is adapted to cover the driver between the driver bar and the roll 216. The guard member 330 is pivotally secured by a pin 332 to the wiper head and has extending downwardly and rearwardly from it an integral arm 334 which is connected by a link 336 (Fig. 2) to the rear end of the driver bar 266. As a result, the guard member 330 is caused to swing upwardly on advance of the driver bar 266 to make room for the driver bar while continuing to cover the driver in the diminishing space between the driver bar and the roll 216. Reversely the guard member is caused to swing downwardly on retraction of the driver bar 266 to insure complete coverage of the driver. However, it will be noted, particularly from an inspection of Fig. 5, that movement of the guard member about its pivot pin 332 causes different portions of that member to become active to cover the driver and these different portions are located different distances from the center of the pivot pin 332. Consequently, the different covering portions of the guard member 330 move at different speeds about the pivot pin 332 during the rotary motion of the guard member 330. To offset this factor, which is apt to result in exposing the driver at some time or other during its travel, the above-described arm 334 and link 336 act as a toggle which upon advance of the driver bar 266 is moved toward a zero position, with the result that movement of the guard member is decelerated, slowing down the covering portions the distance between which and the pin 332 increases at that time. Reversely, on rearward movement of the driver bar 266, the movement of the guard member is accelerated.

The anvil

The previously mentioned anvil 22 has a stem 340 (Fig. 1) which is mounted in a bracket 342 provided on the machine frame 20 at the front of the machine. The stem 340 is adjustable in the bracket 342 heightwise and widthwise of the machine and is held in adjusted position by clamping screws 344, 346, a set screw 348 serving the purpose of making fine adjustments for changing the heightwise position of the anvil. As previously pointed out the anvil engages the inner side or rear face of the insole lip and thus it supports the lip against the thrust of the wiper head 80 as well as the thrust of the driver and the fastening inserted by it. Moreover, the shoe is guided by the contact of the insole lip with the anvil. The anvil, of course, serves the additional

purpose, already described, of deflecting the leading end portion of the fastening after it has fully pierced the margin of the upper and the insole lip to deflect that portion of the fastening and turn it back into the work.

The gripper throw-out mechanism

To adapt the illustrated machine to insert fastenings without utilizing the gripper mechanism either to process certain portions of the work piece where the gripper operation is unnecessary or undesired, or to insert fastenings into other types of work where no gripper operation at all is required, mechanism is provided to render the gripper mechanism inoperative and maintain it in an inoperative out-of-the-way position. To this end the gripper jaw 32 is provided at its upper portion with a toothed segment 350 (Fig. 1) which is adapted to be engaged by a locking pawl 352 pivoted to a boss 354 provided on the other gripper jaw 30. A torsion spring 355, mounted on the hub of the pawl 352 and having one end engaging the pawl and the other the boss 354, tends to depress the pawl 352 into locking engagement with the segment 350. The pawl has an upwardly extending arm 356 the upper end of which is pivotally connected to a link 358 arranged for lengthwise reciprocation and carrying at its rear end a pin 360 (Figs. 1 and 9) the opposite ends of which engage slideways provided in a forked tail piece 362 of the arm 70. Sliding movement of the link 358 toward the left of Fig. 1 permits the spring 355 to move the pawl 352 into locking engagement with the segment 350 and sliding movement of the link 358 toward the right of Fig. 1 lifts the pawl 352 out of engagement with the segment 350. The link 358 is connected at its rear end by the pin 360 to a latch 364 of substantial length. The rear end of the latch 364 is of considerable width, and in order to maintain the pawl 352 in its elevated inoperative position and thus to maintain the gripper operative, the hooked rear end of the latch 364 is normally engaged by a pawl 366 freely rotatable on a transverse shaft 368 rotatably mounted in the machine frame. The pawl 366 is biased by a torsion spring 370 which tends to move the pawl in a clockwise direction, as viewed in Fig. 1, into locking engagement with the latch 364. This movement is limited by a fixed stop pin 372 engaging a slot provided in a depending portion of the pawl 366. To render the gripper mechanism inoperative the latch 364 is elevated out of engagement with the pawl 366 and this is effected by a plate (not shown) secured to the shaft 368 and underlying a portion of the rear end of the latch 364. Secured to the shaft 368 and spaced from the just mentioned plate is a similar plate 376 which overlies the end of a treadle rod 378 upward movement of which, when permitted, causes the plate to be raised with the result that the latch 364 is freed. As soon as the latch 364 is disengaged from the pawl 366 the spring 355 becomes active to slide the link 358 toward the left of Fig. 1 and to depress the pawl 352 into locking engagement with the segment 350 so as to prevent the gripper from closing. Mechanism is provided to prevent the upward movement of the treadle rod 378 even though the rod may be stressed in that direction until a predetermined point in the cycle of gripper operation has been reached, namely when the gripper is substantially in its down position and its jaws are open. In this position of the gripper the cam roll 64 is near the low portion of the cam disk

66. The purpose of this arrangement is to insure that the gripper is open when it is being rendered inoperative, the gripper jaws being locked in their open position, whereupon the gripper is elevated into its inoperative position and held in that position, as will be described. To accomplish this the treadle rod 378 has secured to it a collar 380 the right side of which is provided with a shoulder, as illustrated in Fig. 1. With the collar 380 cooperate two pawls, namely a left-hand pawl 382, adapted to engage beneath the collar 380 and hold it and thus the treadle rod 378 in an elevated position. A right-hand pawl 384 normally engages the shoulder portion of the collar 380 so as to prevent upward movement of the collar and the treadle rod 378. The two pawls 382, 384 are biased by springs (not shown) toward the collar 380 and are pivotally secured to a bracket 386 mounted in the machine frame. To operate the pawls there is provided a pin 388 extending laterally from a link 390 the front end of which is pivotally secured to the gripper operating cam lever 62 and the rear end of which is slotted, the slot being engaged by a pin 392 extending laterally from the bracket 386, this to permit lengthwise reciprocation of the link 390 upon rocking movement of the cam lever 62. As will be described, the pin 388, when being reciprocated by the link 390, is adapted to release either pawl 382 or 384 from engagement with the collar 380. For the purpose of maintaining the gripper mechanism locked-out there is secured on the treadle rod 378 a collar 394 which is adapted on upward movement of the treadle rod to engage a latch 396 pivotally secured at its right-hand end (Fig. 1) to the bracket 386 and normally maintained in a low position against a stop pin 397 by a spring 398. The latch 396 when raised by the collar 394 is adapted to engage behind a shoulder 400 provided on the link 390 when that link is in its forward position in which the gripper is elevated, this preventing the link from returning. Thus the gripper is locked in its elevated inoperative position.

In the position of the machine parts illustrated in Fig. 1, the gripper mechanism is operative and the gripper throw-out mechanism is inoperative with the treadle rod 378 down and its upward movement prevented by the engagement of the pawl 384 with the collar 380. Let it be assumed now that upward pressure is applied to the treadle rod 378. Nothing happens until the low portion of the cam 66 is opposite the cam follower 64 and the link 390 has been moved rearwardly by the cam lever 62, causing the pin 388 to engage the pawl 384 and knock it off the collar 380. Now the treadle rod 378 is free to move up. As will be noted, the upward movement of the treadle rod is thus possible only when the low portion of the cam 66 is opposite the roll 64 or, in other words, when the gripper is down and open. The upward movement of the treadle rod 378 accomplishes two things. First, the plate 376 is elevated, freeing the latch 364 to enable the torsion spring 355 to depress the pawl 352 into locking engagement with the toothed segment 350. Accordingly, the gripper cannot be closed. The other function exercised by the treadle rod is, as already described, the elevation of the latch 396 into a position in which, upon forward movement of the link 390, as the cam roll 64 approaches the high portion of the cam 66, it can snap behind the shoulder 400 and thus hold the cam lever 62 locked out in a position similar to that shown in Fig. 1. It should be noted that

this outward movement of the link 390 by the corresponding movement of the cam lever 62 in a clockwise direction, as viewed in Fig. 1, causes elevation of the gripper into its inoperative position with the gripper jaws open, the gripper being then maintained in that position by reason of the locking of the link 390 against rearward movement by the latch 396. However, the link 390 is not locked in its frontmost position, thus enabling the pawl 382 to engage beneath the collar 380 to hold the treadle rod 378 up. Thus, a slight forward movement of the link 390 occurs even while the gripper mechanism is locked out when the cam roll 64 passes over the highest portion of the cam 66 with the result that the pawl 382 is moved out of engagement with the collar 380 once during each cycle, namely when the highest point of the cam 66 is opposite the cam roll 64. Accordingly, the treadle rod 378 can be lowered again only at that time. When it is desired to throw the gripper mechanism into operation, the treadle (not shown) operating the treadle rod 378 is released but, as pointed out, the treadle rod cannot move down since it is locked by the pawl 382. The pawl 382 becomes automatically unlocked when the cam roll 64 passes over the highest portion of the cam 66, causing the above-mentioned slight forward movement of the link 390 and the pawl releasing pin 388. As the treadle rod 378 goes down the collar 394 also is lowered, permitting the spring 398 to pull the latch 396 out of engagement with the shoulder 400, thus enabling the link 390 again to move rearwardly in the machine and accordingly permitting the gripper to descend and to be operated in the normal way. Of course, the lowering of the treadle rod 378 also causes the plate 376 to be lowered, with the result that the latch 364 is lowered. To unlock the gripper jaw 32 by raising the locking pawl 352 there is secured on the rearward extension 138 of the wiper head a catch 402 (Figs. 1 and 2) which, during the rearward movement of the wiper head, engages the hooked end of the latch 364 and pulls the latch rearwardly into locking engagement with the pawl 366, thereby sliding the link 358 rearwardly in the machine and elevating the pawl 352 against the pressure of its spring 355.

The Machine Operation

In the operation of the illustrated machine, a work piece comprising an upper U assembled on a last L carrying a lipped insole I on its bottom is presented to the machine with the last bottom up and the inner side of the insole lip resting against the anvil 22 at a location where the fastening inserting operation is to begin. The margin of the upper is placed between the open jaws of the gripper 24 which is in its lowermost position. The clutch controlling the rotation of the cam shaft 28 is then engaged to initiate the operation of the machine. The different cams controlling the operations of the different actuating mechanisms of the machine are so designed that the sequence of the operations in one cycle of the machine is as follows. The wire receiving and severing roll 216 is first rotated into its wire receiving position while the wiper head is still in its rearward inoperative position and the gripper is down and open. Thereupon the wire feeding mechanism is actuated to feed a length of wire into the roll 216 which then is rotated into its fastening inserting position, thereby severing the fed-in length of wire from the strand to form a fastening and to locate the fastening in

the path of the operative movement of the driver. Then the gripper is closed upon the upper and elevated to tension the upper heightwise of the last, as illustrated in Figs. 10 and 11. Simultaneously with the initiation of the gripper operation, the wiper head 80 begins its forward movement into engagement with the tensioned margin of the upper. The gripper jaws are slightly opened, due to the dip 76 in the gripper actuating cam 66 at that point, to permit slippage of the upper between the gripper jaws as the gripper remains in its elevated position, thus to enable the wiper head 80 to wipe the margin of the upper inwardly over the insole into firm engagement with the feather portion of the insole and the lip and well into the crease formed by the feather and the lip, without tearing the upper. Moreover, due to the fact that the gripper 24 is suspended on the pivot pin 71 and thus can swing transversely of the shoe presented to the machine, it can participate, while in its elevated upper tensioning position, in the inward wiping movement of the wiper head, thus further insuring against any tearing of the upper. The wiper head, having completed its wiping operation, is held in its forward position to hold the margin of the upper in its last position while the driver is released by the tripping of the latch 290 to insert a fastening through the margin of the upper and the lip in the manner described (see Figs. 12 and 13). Thereupon the various instrumentalities are returned to their initial positions and a new portion of the shoe is presented to the operating instrumentalities preparatory to the next upper tensioning and fastening inserting operation.

The wire feeding and severing mechanisms and the mechanism for actuating the throat member and the driver, above described but not claimed herein, are made the subject matter of a divisional application Serial No. 652,582, filed on March 7, 1946, now Patent No. 2,455,370, granted December 7, 1948, in my name. The driver guard mechanism, above described but not claimed herein, is made the subject matter of another divisional application Serial No. 660,-169, filed on April 6, 1946, now Patent No. 2,455,-371, granted December 7, 1948, in my name. The gripper mechanism, above described but not claimed herein, is made the subject matter of still another divisional application Serial No. 667,-843, filed on May 7, 1946, now Patent No. 2,432,-165, granted December 9, 1947, in my name.

Having described my invention, what I claim as new and desire to secure by Letters Patent of the United States is:

1. In a fastening inserting machine, a fastening guiding throat member, a driver for driving fastenings into a work piece presented to said throat member, fastening engaging means disposed at one side of the work and arranged during the driving operation to deflect each fastening into that side of the work, and additional fastening engaging means disposed at the opposite side of the work and arranged during the continued driving operation to deflect each fastening into the last mentioned side of the work, the additional fastening engaging means being associated with said throat member.

2. In a fastening inserting machine, a work contacting throat member, a driver movable in the throat member to insert fastenings into the work, means adapted to engage the side of the work opposite that engaged by the throat member and arranged to deflect the leading end portion of the fastening after it has fully pierced the work so as to cause said leading end portion to reenter the work and emerge from the side of entry of the work, and means associated with the throat member to cause the emerging leading end portion of the fastening to reenter the work a second time.

fastening after it has fully pierced the work so as to cause said leading end portion to reenter the work and emerge from the side of entry of the work, and means associated with the throat member to cause the emerging leading end portion of the fastening to reenter the work a second time.

3. In a fastening inserting machine, a work contacting throat member, a driver movable in the throat member to insert fastenings into the work, means adapted to engage the side of the work opposite that engaged by the throat member and arranged to deflect the leading end portion of the fastening after it has fully pierced the work so as to cause said leading end portion to reenter the work and emerge from the side of entry of the work, and a deflecting face provided on the throat member and adapted to engage the emerging end portion of the fastening and to anchor it within the work.

4. In a fastening inserting machine, a movable work engaging throat member, a driver movable in the throat member to insert single-legged fastenings into the work, an anvil adapted to engage the side of the work opposite that engaged by the throat member and arranged to deflect the leading end portion of the fastening after it has fully pierced the work to cause said leading end portion to reenter the work and emerge from the side of entry of the work, and a deflecting face provided on the throat member and adapted to engage the emerging leading end portion of the fastening to anchor it within the work.

5. In a fastening inserting machine, a work contacting throat member, a driver movable in the throat member to insert fastenings into the work, an anvil adapted to engage the side of the work opposite that engaged by the throat member and arranged to deflect the leading end portion of the fastening after it has fully pierced the work so as to cause said leading end portion to reenter the work and emerge from the side of entry of the work, and a deflecting face provided on the throat member and adapted to curve the emerging leading end portion of the fastening so as to cause said leading end portion to reenter the work at a point spaced from the point of entry.

6. In a fastening inserting machine, a work engaging throat member, fastening inserting means including a driver cooperating with the throat member to insert single-legged fastenings, means for actuating the driver to insert a fastening and to countersink the trailing end portion thereof in the work, an anvil adapted to engage the side of the work opposite that engaged by the throat member and arranged to deflect the leading end portion of the fastening after it has fully pierced the work so as to cause said leading end portion to reenter the work and emerge from the side of entry of the work, and means associated with the throat member and adapted to cause the emerging leading end portion of the fastening to reenter the work a second time.

7. In a machine for fastening a shoe upper in last position to the rib of a sole member, a throat member engaging the margin of the upper positioned against one side of the rib, a driver movable in the throat member successively to insert fastenings through the margin of the upper and the rib, means for actuating the driver to countersink the trailing end portion of each fastening when being driven, an anvil engaging the other side of the rib and adapted to receive the leading end portion of the fastening and to deflect it back to cause it to emerge from the surface of the

19

margin of the upper, and means associated with the throat member and adapted to cause the emerging leading end portion of the fastening to reenter the work a second time.

8. In a machine for fastening a shoe upper in lasted position to the rib of a sole member, a movable throat member engaging the margin of the upper positioned against one side of the rib, a driver movable in the throat member successively to insert fastenings through the margin of the upper and the rib, means for actuating the driver to countersink the trailing end portion of each fastening when being driven, an anvil engaging the other side of the rib and adapted to receive the leading end portion of the fastening and to deflect it back to cause it to emerge from the surface of the margin of the upper, and a deflecting face provided on the throat member and adapted to engage the emerging leading end portion of the fastening and to anchor it within the work.

9. In a machine for fastening a shoe upper in lasted position to the rib of a sole member, a movable throat member engaging the margin of the upper positioned against one side of the rib, a driver movable in the throat member successively to insert fastenings through the margin of the upper and the rib, means for actuating the driver to countersink the trailing end portion of each fastening when being driven, an anvil engaging the other side of the rib and adapted to receive the leading end portion of the fastening and to deflect it back to cause it to emerge from the surface of the margin of the upper, and a deflecting face provided on the throat member and adapted to curve the emerging leading end portion of the fastening to cause it to reenter the work a second time at a point spaced from the point of entry.

10. In a machine for fastening a shoe upper in lasted position to the rib of a sole member, a movable throat member engaging the margin of the upper positioned against one side of the rib, a driver movable in the throat member successively to insert fastenings through the margin of the upper and the rib, means for actuating the driver to countersink the trailing end portion of each fastening when being driven, an anvil engaging the other side of the rib and adapted to receive the leading end portion of the fastening and to deflect it back to cause it to emerge from the surface of the margin of the upper, and a deflecting face provided on the throat member and adapted to curve the emerging leading end portion of the fastening to cause it to reenter the work a second time at a point lying between the points of entry and emergence.

11. That improvement in methods of fasten-

20

ing a shoe upper in lasted position to the rib of a sole member which consists in holding the margin of the upper in lasted relation against the outer face of the rib, driving a fastening through the upper and the rib, deflecting the emerging leading end portion of the fastening back into the work, continuing to drive the fastening to cause the leading end portion thereof to reemerge from the surface of the margin of the upper, deflecting the reemerged end portion of the fastening to cause it to reenter the work a second time, and countersinking the trailing end portion of the fastening.

12. That improvement in methods of fastening a shoe upper in lasted position to the rib of a sole member which consists in holding the margin of the upper in lasted relation against the outer face of the rib, driving a fastening through the upper and the rib, deflecting the emerging leading end portion of the fastening back into the work, continuing to drive the fastening to cause the leading end portion thereof to reemerge from the surface of the margin of the upper, and curving the reemerged end portion of the fastening to cause it to reenter the work a second time at a point spaced from the point of entry of the fastening on the surface of the margin of the upper.

13. The improvement in methods of fastening a shoe upper in lasted position to the rib of a sole member which consists in holding the margin of the upper in lasted relation against the outer face of the rib, driving a fastening through the upper and the rib, deflecting the emerging leading end portion of the fastening back into the work, continuing to drive the fastening to cause the leading end portion thereof to reemerge from the surface of the margin of the upper, curving the reemerged end portion of the fastening to cause it to reenter the work a second time at a point lying between the points of entry and emergence, and countersinking the trailing end portion of the fastening.
